BOWL OR SIMILAR ARTICLE

Robert Y. Allen, Encino, Melvin Shaw, Beverly Hills, and Evan K. Shaw, Los Angeles, Calif., assignors to Metlox Manufacturing Company, Manhattan Beach, Calif., a corporation of California

Application March 29, 1948, Serial No. 145,425

Term of patent 14 years

(Cl. D44—29)

To all whom it may concern:

Be it known that we, Robert Y. Allen, residing at Encino, in the county of Los Angeles, State of California, Melvin Shaw, residing at Beverly Hills, in the county of Los Angeles, State of California, and Evan K. Shaw, residing at Los Angeles, in the county of Los Angeles, State of California, all citizens of the United States, have invented a new, original, and ornamental Design for Bowls or Similar Articles, of which the following is a specification, reference being had to the accompanying drawing, forming part thereof, in which:

Fig. 1 is a top fragmentary plan view of a bowl or similar article, showing our new design;

Fig. 2 is a side elevational view thereof;

Fig. 3 is an end elevational view as seen from the right of Fig. 2; and

Fig. 4 is a bottom plan view thereof.

The dominant features of the design reside in the handle portion drawn in full lines as shown.

We claim:

The ornamental design for a bowl or similar article, as shown and described.

ROBERT Y. ALLEN.
MELVIN SHAW.
EVAN K. SHAW.
